by the Colgate-Palmolive Co.

Primary Examiner—Wallace R. Burke

Assistant Examiner—Lavone D. Tabor

Attorney, Agent, or Firm—Sullivan, Robert C.; Richard
J. Ancel[57] **CLAIM**The ornamental design for a toothbrush handle, as
shown and described.**DESCRIPTION**FIG. 1 is a front elevational view of a toothbrush handle
showing our new design;

FIG. 2 is a top plan view thereof;

FIG. 3 is a bottom plan view thereof;

FIG. 4 is a rear elevational view thereof; and,

FIG. 5 is a perspective view thereof.

The structure shown in phantom or broken lines in the
Figures forms no part of the claimed design and is pres-
ent only to illustrate the environment.

The undisclosed end is unornamented.
